FLASHLIGHT BATTERY CLAMP FOR A BICYCLE

William Bartunek, Yonkers, N.Y., assignor to P. R.
Mallory & Co. Inc., Indianapolis, Ind.

Filed Sept. 17, 1973, Ser. No. 398,110

Term of patent 14 years

Int. Cl. D8—08

U.S. Cl. D8—247

FIG. 1

FIG. 2

FIG. 3

FIG.4

FIG. 5

FIG. 6

FIG. 1 is a perspective view of a flashlight battery clamp for a bicycle, the broken lines being for illustrative purposes only.

FIG. 2 is an end view indicating the flashlight clamp above shown in FIG. 1.

FIG. 3 is a top view indicating the bicycle clamp illustrated in the above figures.

FIG. 4 is a bottom view of the bicycle clamp as shown as the obverse of the structure in FIG. 3.

FIG. 5 is a side view of the bicycle clamp shown in the above figures; and

FIG. 6 is another view of the clamp taken opposite the side shown in FIG. 5.

I claim:

The ornamental design for a flashlight battery clamp for a bicycle, as shown and described.
